Des. 64

William Jackson, Syracuse, N. Y.
Letters Patent (Design No. 64) dated 25th July 1840

The Schedule referred to in these Letters Patent and
making part of the same.

To all whom it may concern:

Be it known that I, William Jackson, of Syracuse, in the County of Onondaga, and State of New York, have invented or produced a new design for an ornamented Cooking Stove, and I do hereby declare that the following is a full, clear and exact description thereof, reference being had to the accompanying drawings making part of this specification, in which Fig. 1. is a perspective view of a stove after my design; - Fig. 2 is an enlarged view of one of the sides, (both sides being alike) - Fig. 3 is the back plate; and Figs 4 the front of the stove. Fig. 5 is a section of the mouldings of the raised panels upon the sides and Fig. 6, a section of those upon the ends. -

The panels are filled with ornamental figures composed of scrolls, foliage &c. not easily described in words, but fully represented in the drawings - The figure 22. at each end of the sides, is a vase with a vine rising therefrom. The band indicated at b b &c. is continued around all the panels.

What I claim as my invention, and desire to secure by Letters Patent, is the combination and arrangement of ornamental figures herein shown and described, forming a Design for an ornamented Cooking Stove.
